(57) **CLAIM**

The ornamental design for a laundry appliance, as shown and described.

DESCRIPTION

FIG. 1 is a perspective view of a laundry appliance showing my new design;

FIG. 2 is a front view thereof;

FIG. 3 is a top view thereof; and,

FIG. 4 is a right side view thereof, a left side view being a mirror image thereof.

The broken line showing of the various surface details in FIGS. 1-4 are for the purpose of illustration only and form no part of the claimed design. The stippling shown in FIGS. 1 and 2 is provided to illustrate contrasting surfaces, and does not represent any particular color, pattern or surface texture.
